TROLLEY NIP

Walter Ray Fortney, Morgantown, W. Va.

Application February 10, 1950, Serial No. 143,522

4 Claims. (Cl. 200—115.5)

1

This invention relates to a trolley nip, and more particularly to a contact member for engagement with an overhead electrical supply line for use in auxiliary equipment in mines or the like.

It is an object of this invention to provide a trolley head of the kind to be more particularly described hereinafter having a fuse rigidly mounted within an insulating handle, the fuse being supported within the handle and connected to the cable in such a manner that the fuse will be clampingly secured, at its opposite ends to the terminals, connecting the fuse in the electric circuit.

Another object of this invention is to provide a trolley nip of this kind wherein the fuse may be readily disengaged from its contact with the auxiliary cable and the hook connection for engagement with the trolley wire.

Still another object of this invention is to provide a trolley nip of this kind wherein the fuse is slidably engaged within the insulated handle and clampingly secured to the auxiliary cable at one end. The other end of the fuse is clampingly secured to the trolley hook which is removable from the insulating handle in such a manner that, upon failure of the fuse, the entire fuse and its connections to both the cable and the hook may be readily removed from the handle for the installation of a new fuse in its place, to be replaced within the handle.

With the above and other objects in view, my invention consists in the arrangement, combination and details of construction disclosed in the drawings and specification, and then more particularly pointed out in the appended claims.

In the drawings:

Figure 1 is a longitudinal section, partly broken away, of a trolley nip constructed to an embodiment of my invention.

Figure 2 is a transverse section, taken on the line 2—2 of Figure 1.

Figure 3 is a transverse section, taken on the line 3—3 of Figure 1.

Figure 4 is a transverse section through the trolley nip, taken on the line 4—4 of Figure 1, showing the clamping engagement of one of the fuse clamping members with an end of the fuse.

Figure 5 is a transverse section, taken on the line 5—5 of Figure 1.

Figure 6 is a transverse section, taken on the line 6—6, at the upper end of Figure 1.

Figure 7 is an enlarged side elevation of the segmental nut member removed from the assembly of the trolley nip, and showing the nut segments in spaced relation.

2

Referring to the drawings, the numeral 10 designates generally a trolley nip constructed according to an embodiment of my invention for use in mines or other places where a trolley power line is provided, the nip 10 being engageable with the trolley line for supplying electrical current to auxiliary equipment used in the mine. The trolley nip 10 of this invention is provided with a fuse 11, contained within the outer casing 12 for breaking the circuit to the auxiliary equipment upon overheating or overloading of the cable in the circuit to the auxiliary equipment from the trolley or power line.

The fuse 11 is slidably engaged within the outer casing 12, of the trolley 10 to be readily removed therefrom when it is required, or desired, to remove the fuse to be replaced by another.

The outer casing 12, of the trolley nip 10, is formed as a tubular, cylindrical member made of any suitable, flexible insulating material generally used for devices of this kind. The casing 12 is open at the opposite ends thereof, both ends of the casing being threaded internally for receiving therein closure members for the opposite ends. As considerable heat is frequently generated within the housing or casing 12, an asbestos lining 14 is fixedly secured to the inner surface of the casing between the opposite ends thereof, the lining 14 terminating in spaced relation to the opposite ends of the outer casing in such a manner that the members which are threadably engaged in the opposite open ends of the casing may be engaged with the insulating material and the asbestos lining 14 will abut, at its opposite ends, with the inner faces of the closure members upon the opposite ends.

A cylindrical or tubular bushing 15 is threadably engaged in one open end of the casing 12, the bushing 15 being threaded on both the outer and inner sides thereof, as clearly noted in Figure 1 of the drawings. The bushing 15, when engaged in one open end of the casing 12 will abut, at its inner end, against one end of the asbestos lining 14 and the other end of the bushing 15 will be extended a short distance above the upper end of the casing 12. Suitable glue or cement should be placed on the outer threads of the bushing 15 for securing the bushing in the casing 12.

A suitable, annular insulating disc 16 is threadably engaged on the upper end of the bushing 15, the lower side of the insulator disc 16 abutting one end of the casing 12. A transverse set screw, or dowel 17 is threadably en-

gaged through an annular shoulder 18, on the upper side of the disc 16, for fixedly securing the insulator disc 16 onto the trolley nip 10. The insulator disc 16 is of a suitable insulating material, and its purpose is generally recognized in the use of devices of this kind.

An upper connector head 19 is threadably engaged within the bushing 15, as shown in Figure 1 of the drawings, the connector head 19 being formed of brass, or other suitable conducting material to provide a suitable electrical connection from the hook 20 through the casing 12 to the cable 21, and in turn to the auxiliary electrical equipment to be operated from the power line with which the trolley nip 10 may be engaged. The connector head 19 is substantially cylindrical in configuration, being threaded on the periphery thereof for threaded engagement within the bushing 15 for securing the head 19 within the casing 12. As the upper head 19 is secured within the casing 12, the upper end of the head 19 will be normally disposed flush with the upper edge of the bushing on the upper side of the insulator disc 16 and the lower or inner ends of the head 19 will be terminated substantially in alignment with the shoulder 18 formed at the terminal ends of the asbestos lining 14. A threaded bore 25 is formed axially of the cylindrical connector head 19 for receiving a threaded clamping nut 26.

The clamping nut 26 is formed of a pair of nut elements 27 and 28, which when properly secured together form the split nut member 26. One of the nut segments 27 is formed with threaded transverse bores 29 through the head section 30 thereof. The other nut segment 28 is formed with a pair of transverse bores 31 therethrough for alignment, when disposed in nut-forming engagement with the other nut segment 28, with the bores 29 whereupon the screws 32 may be threadably engaged in the threaded bores 29 for aligning the nut segments 27 and 28 together. The screws 32 are threadably engaged in one of the nut elements, as the nut element 28, and slidably in the bore 31 of the other nut element 28 in the manner of a dowel for properly aligning the exterior threads of the nut elements to provide for the proper threaded engagement of the nut 26 in the inner threaded bore of the connector head 19. The nut segments 27 and 28 are loosely connected together by the screws 32, and, when the nut 26 is engaged in the threaded bore 25, the connector head 19 will be properly aligned therein by the engagement of the threads with the threads of the head 19.

The hook 20, which is formed with an upper bill 35 and a depending shank 36 is adapted to be clampingly secured within the nut members 26 at the upper end of the trolley nip 10.

The lower end of the hook shank 36 is adapted to be slidably engaged in the concave portion of the opened-nut sections 27 and 28, to be secured therein when the connector head 19 is threadably engaged in the bushing 15. The lower end of the nut member 26 is slightly flared at the lower end of the central bore for receiving the outwardly flared lower end of the shank 36, the engagement of the outwardly flared lower end 40 being engageable on the tapered shoulder 41 for holding the hook 20 against upward sliding movement when it is secured between the nut segments 27 and 28.

The extreme lower end of the connector head 19 is of a substantially reduced cross section and is bifurcated (Figure 3) to provide a pair of clamping arms 42 and 43 slightly spaced apart

5 for receiving therebetween an upper bifurcated terminal connector lug 44 on the upper end 45 of the fuse 11. A transverse clamping bolt 46 is slidably engaged through one of the clamping arms 42 and 43 and threadably engaged with the other arm 42 for securely clamping the connector lug 44 therebetween.

10 The connector head 19 is also formed with a plurality of longitudinally extending vents 47 (Figures 1, 2 and 6) which open at their outer ends to the atmosphere, and open at their inner ends into the space defined within the casing 12 between the opposite ends thereof. The lower end of the vents 47 open above the clamping members 42 and 43 on one side thereof, as clearly noted in Figure 1 of the drawings. The connector lug 49, on the other end of the fuse 11 is provided with an opening 50 which is directed laterally of the axis of the fuse 11, the connector lug 49 being bifurcated with the axis positioned perpendicular to the opening of the body of the fuse 11 and the opening of the other connector lug 45.

15 A thrust plug 51 is threadably engaged in the other lower end of the casing 12, the thrust plug 51 being provided with a central bore 52 therethrough opening at one end exteriorly of the casing 12 and at the other end within the casing in the space within which the fuse 11 is to be positioned. The cable 21, connected to the auxiliary electrical equipment to be supplied through the trolley nip 10 is slidably engaged through the bore 52. A suitable cement may be placed about the thrust plug 51 for securely sealing the thrust plug 35 in the casing 12.

20 A lower connector head 54 is slidably engaged in the lower end of the casing 12, the head 54 being adapted to be connected to the connector member 49 and to the wires 55, carried by the cable 21. The lower head 54 is formed with a central body section 56 having a clamping member 57 extending in one direction therefrom and a clamping member 58 extending in the other direction.

25 The lower clamping member 57 (Figures 1 and 5) is formed with a fixed clamping jaw 59, the clamping jaw 59 being fixed to, or preferably formed integral with, the central body portion 56. A movable jaw member 60 is adapted to be clampingly secured to the fixed jaw member 59 by a transverse bolt or screw 61 which is threadably engaged in the fixed jaw member 59 for clampingly securing the wires 55 in clamping engagement between the fixed jaw 59 and movable jaw 60 at the lower end of the fuse 11. The other clamping member 58, extending upwardly from the central body 56, as clearly noted in Figure 1 of the drawings, is also bifurcated to define a pair of transversely spaced apart clamping jaws 62 and 64, noted in Figure 4 of the drawings. The clamping jaws 62 and 64 are adapted to receive therebetween the lower connector member 49 having the transversely extending aperture 60. A transverse bolt 65 is threadably engaged through the clamping jaw members 62 and 64 for clampingly securing the lower connector member 49 therebetween.

30 In the use and operation of the trolley nip 10, described above, the nut member 26 is initially threaded out of engagement with the connector head 19 and the head 19 is threaded out of engagement with the bushing member 15. The fuse 11 and head 54 are slidably removed from the outer casing 12.

35 The cable 21 is then extended through the

aperture 52 in the plug 51 and is extended through the length of the casing 12. The wires 55 are then clampingly engaged in the wire clamp 57, on one end of the lower connector head 54 which is clampingly engaged with one end of the fuse 11. The upper end of the fuse 11 is then clampingly engaged between the jaw members 42 and 43 of the upper head 19 by the tightening of the transverse screw 46. The lower head 54 and the head 19 are then engaged in the casing 16 with the fuse 11 secured therebetween. The upper head 19 may be threadably engaged within the bushing 15, the loose engagement of the cable 21, in the aperture or the bore 52 providing for the rotative tightening of the upper head 19 within the bushing 15.

The hook 20 is then secured to the trolley nip 10 by the threaded engagement of the nut member 26 in the threaded recess 25 of the upper head 19. It will be noted that the nut member 26 is only engageable in the upper head 19 when the segments 27 and 28 are properly aligned together with the transverse bolt 32. The hook 20, which includes the lower shank 36 may be removed from the nut member 26 when the nut member 26 is removed from its assembly in the upper head 19 and the nut segments 27 and 28 are separated from engagement with the transverse bolts 32, as clearly shown in Figure 7 of the drawings.

I do not mean to confine myself to the exact details of construction herein disclosed, but claim all variations falling within the purview of the appended claims.

I claim:

1. In a trolley, an elongated insulated tubular casing open at its ends, a tubular plug removably engaged in one end of the casing, an insulated conductive cable passing into the interior of the casing through and slidably and rotatably engaging the bore of the plug, a tubular bushing threaded into the other end of the casing, said bushing having a threaded bore, a connector head removably threaded in and extending through the threaded bore of said tubular bushing, said head having first clamping means on its axially inward end positioned within the interior of the casing axially inwardly of said tubular bushing, an axially elongated fuse positioned in the interior of the casing between said plug and said connector head, said fuse being smaller in diameter than the interior of the casing, a first connector lug separably connected to the end of said fuse adjacent to said plug, said first connector lug having a portion of enlarged diameter slidably and rotatably engaging the interior of the casing, said first connector lug further having second clamping means connecting said conductive cable to said first lug within the interior of the casing, means separably connecting said first connector lug with the fuse, a second connector lug on the other end of the fuse with which said first clamping means is clampably engaged.

2. In a trolley, an elongated insulated tubular casing open at its ends, a tubular plug removably engaged in one end of the casing, an insulated conductive cable passing into the interior of the casing through and slidably and rotatably engaging the bore of the plug, a tubular bushing threaded into the other end of the casing, said bushing having a threaded bore, a connector head removably threaded in and extending through the threaded bore of said tubular bushing, said head having first clamping means on its axially inward end positioned within the in-

terior of the casing axially inwardly of said tubular bushing, an axially elongated fuse positioned in the interior of the casing between said plug and said connector head, said fuse being smaller in diameter than the interior of the casing, a first connector lug separably connected to the end of said fuse adjacent to said plug, said first connector lug having a portion of enlarged diameter slidably and rotatably engaging the interior of the casing, said first connector lug further having second clamping means connecting said conductive cable to said first lug within the interior of the casing, means separably connecting said first connector lug with the fuse, a second connector lug on the other end of the fuse with which said first clamping means is clampably engaged, said first clamping means being engaged endwise with said second connector lug whereby said fuse can be separated from said first clamping means only by endwise movement of said fuse and said connector head relative to each other with said first clamping means released.

3. In a trolley, an elongated insulated tubular casing open at its ends, a tubular plug removably engaged in one end of the casing, an insulated conductive cable passing into the interior of the casing through and slidably and rotatably engaging the bore of the plug, a tubular bushing threaded into the other end of the casing, said bushing having a threaded bore, a connector head removably threaded in and extending through the threaded bore of said tubular bushing, said head having first clamping means on its axially inward end positioned within the interior of the casing axially inwardly of said tubular bushing, an axially elongated fuse positioned in the interior of the casing between said plug and said connector head, said fuse being smaller in diameter than the interior of the casing, a first connector lug separably connected to the end of said fuse adjacent to said plug, said first connector lug having a portion of enlarged diameter slidably and rotatably engaging the interior of the casing, said first connector lug further having second clamping means connecting said conductive cable to said first lug within the interior of the casing, connecting means separably connecting said first connector lug with the fuse, a second connector lug on the other end of the fuse with which said first clamping means is clampably engaged, said first clamping means being engaged endwise with said second connector lug whereby said fuse can be separated from said first clamping means only by endwise movement of said fuse and said connector head relative to each other with said first clamping means released, said first connector lug and said connecting means being engaged sidewise with each other whereby said fuse can be separated from said second connector lug only by sidewise movement of the fuse and said first connector lug relative to each other.

4. In a trolley, an elongated insulated tubular casing open at its ends, a tubular plug removably engaged in one end of the casing, an insulated conductive cable passing into the interior of the casing through and slidably and rotatably engaging the bore of the plug, a tubular bushing threaded into the other end of the casing, said bushing having a threaded bore, a connector head removably threaded in and extending through the threaded bore of said tubular bushing, said head having first clamping means on its axially inward end positioned within the in-

terior of the casing axially inwardly of said tubular bushing, an axially elongated fuse positioned in the interior of the casing between said plug and said connector head, said fuse being smaller in diameter than the interior of the casing, a first connector lug separably connected to the end of said fuse adjacent to said plug, said first connector lug having a portion of enlarged diameter slidably and rotatably engaging the interior of the casing, said first connector lug further having second clamping means connecting said conductive cable to said first lug within the interior of the casing, means separably connecting said first connector lug with the fuse, a second connector lug on the other end 15 of the fuse with which said first clamping means is clampably engaged, and a conductive hook

having a shank removably secured in said connector head whereby said hook can be removed from said connector head without removing the head from the tubular bushing.
